(57) **CLAIM**

The ornamental design for a meat thermometer as shown and described.

DESCRIPTION

FIG. 1 is a front, top, and left perspective view of a meat thermometer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof;

FIG. 8 is a rear, bottom, and right perspective view thereof; and,

FIG. 9 is a perspective view shown in a configuration of use. The broken lines in the drawings depict portions of the meat thermometer that form no part of the claimed design.
